UNITED STATES PATENT OFFICE.

WILLIAM ANDERSON, OF WESTMINSTER, ENGLAND.

RECOIL-CHECK FOR ORDNANCE.

SPECIFICATION forming part of Letters Patent No. 424,947, dated April 8, 1890.

Application filed July 10, 1889. Serial No. 316,999. (No model.) Patented in England January 18, 1888, No. 818.

To all whom it may concern:

Be it known that I, WILLIAM ANDERSON, engineer, a subject of the Queen of Great Britain, residing at 3 Whitehall Place, in the city of Westminster, England, have invented certain new and useful Improvements in Disappearing Mountings for Guns, (for which I have received Letters Patent in Great Britain, dated January 18, 1888, No. 818,) of which the following is a specification.

This invention relates to gun-mountings in which the gun is carried on oscillating arms, as in what is known as the "Moncrieff system." These mountings I so construct that the supporting-arms have to pass somewhat beyond the perpendicular to bring the gun into firing position, so that the gun at the first part of recoil has to rise a little before falling, which diminishes the strain on the holding-down connection. The hydraulic cylinder used for checking the recoil I place in front of the arms, and a cross-head attached to the arms I connect to the end of its piston-rod. Beneath the recoil-cylinder is carried a storage cylinder or cylinders, in which rams slide that are held down by disk-springs. A passage is formed from the front of the cylinder to a valve held down by a spring, and which opens toward the storage-cylinder. It can be opened by a hand-lever, but cannot be prevented from opening.

The action of the apparatus is as follows: Liquid is filled into the cylinder and a certain initial pressure put on the springs when the gun is up. The gun is then fired, and in recoil the liquid is forced through the valve into the storage-cylinder, storing up sufficient power to raise the gun for the next round, the excess being absorbed in friction of the passages. The valve then closes automatically, retaining the liquid in the storage-cylinder, and the gun is reloaded. When the loading is completed, the valve is opened and the pressure allowed to act on the piston and raise the gun to the firing position.

Figure 1 of the drawings hereunto annexed is a side elevation of a gun-mounting constructed in the above manner. The gun is shown in its firing position. Fig. 2 is a plan view with the gun in loading position; and Fig. 3, an end view with some parts cut away.

Fig. 4 is a cross-section through the recoil and storage cylinders, on the line 4-4 of Fig. 2; Fig. 5, a side elevation, partly in section, of these cylinders; and Fig. 6 is a longitudinal section of one of the storage-cylinders. Fig. 7 is a diagram view, partly in section, showing the connection between the recoil-cylinder and the storage-cylinder, and showing the parts in firing position. Fig. 8 is a similar view showing the parts as they appear after recoil.

A are the arms upon which the gun is mounted. B is the shaft upon which they turn, and which, as shown in Fig. 1, is in rear of the trunnions of the gun when the gun is in its firing position. The shaft B is carried by a rectangular frame, consisting of the two parallel sides C C, connected together at one end by the cross-piece or pivot-plate D and at the other by the cross-piece E, supported on rollers E'.

F is the oscillating recoil-cylinder, in which slides a piston, whose rod passes through the rear cover and is connected to a cross-head G, attached to the arms or levers A. The trunnions of the cylinder F are received in bearings in the front end of the frame C, as shown in Figs. 1 and 4.

H H are two storage-cylinders fixed beneath the cylinder F. H' H' are rams sliding in these cylinders and forced inward by springs I, as shown in Fig. 6. The cylinders at their front ends communicate one with the other by a passage h, and one of them is connected by a pipe J with one of the hollow trunnions of the cylinder F. The hollow trunnion communicates with a passage f in the side of the cylinder F, which leads to the rear end of the cylinder with which it communicates at f'. (See Fig. 2.) Where the pipe J enters the storage-cylinder a throttling arrangement is applied by which the recoil can be regulated. In the hollow trunnion is a valve K, held down by a spring against the end of a passage leading from the hollow trunnion to the front end of the recoil-cylinder. The end of the hollow trunnion is closed, as shown in Fig. 4, and through its closed end passes a screw L, by turning which the valve can be drawn away from its seat.

M is a small tank above the recoil-cylinder

and containing liquid which passes into the recoil-cylinder in front of the piston when the piston is drawn back by the recoil of the gun. After the gun has recoiled and the valve K 5 has been opened to allow liquid to be forced back from the storage-cylinders to the recoil-cylinder the piston is forced forward to its former position into the cylinder, and the liquid which has passed into the cylinder from 10 the tank is forced back into the tank through the small passages N. As the piston arrives at the end of its stroke a portion of the piston passes over and covers these openings one after the other, and so brings the gun to rest 15 in a gradual manner. Similarly when the gun recoils it may be gradually brought to rest by a projection from the piston gradually obstructing the passage of liquid from the cylinder to the spring-loaded valve, past which 20 the liquid has to be forced before it enters the storage-cylinders.

What I claim is—

1. The combination, substantially as herein-before set forth, of the bed-frame, the gun, its 25 trunnions, the vertical rocking arms pivoted at their lower ends to the bed-frame and at their upper ends supporting the gun-trunnions, the hydraulic recoil-cylinder, the trunnions of the cylinder in the bed-frame, the 30 storage-cylinder connected to and rocking with the recoil-cylinder, a passage connecting the storage-cylinder with the recoil-cylinder, a valve in said passage, the spring-actuated ram in the storage-cylinder, the piston in the 35 recoil-cylinder, and the piston-rod connected to the vertical rocking arms at their lower ends

in front of the pivotal connection with the bed-frame.

2. The combination, substantially as herein-before set forth, of the bed-frame, the vertical 40 pivot supporting its front end, rollers supporting the rear end of the frame, the gun, the vertical rocking arms pivoted at their lower ends to the frame and supporting the gun in their upper ends, the recoil-cylinder, a pair of 45 storage-cylinders rigidly secured thereto, and a fluid-passage connecting them, a valve interposed in said passage, a passage between the storage-cylinders, spring-actuated rams in the storage-cylinders, a piston working in 50 the recoil-cylinder, and a piston-rod connected to the lower end of the rocking arms in front of their pivotal connection with the bed-frame.

3. The combination, substantially as herein-before set forth, of the gun, the bed-frame, the 55 rocking arms pivoted to the bed-frame and supporting the gun at their upper ends, the recoil and storage cylinders rigidly connected together, the trunnions of the recoil-cylinder, connected with the bed-frame, the spring-actuated 60 ram in the storage-cylinder, the piston working in the recoil-cylinder, the piston-rod connected thereto and pivotally connected with the rocking arms, a passage leading from the storage-cylinder and connected with 65 the recoil-cylinder through one of its trunnions, and a valve interposed in this passage.

WILLIAM ANDERSON.
